US00D966184S

(12) **United States Design Patent** (10) **Patent No.:** **US D966,184 S**
Cheng (45) **Date of Patent:** **** Oct. 11, 2022**

(54) **BATTERY**

- (71) Applicant: **JUHEYUAN SCIENCE & TECHNOLOGY CO., LTD.**, Shenzhen (CN)
- (72) Inventor: **Kewen Cheng**, Shenzhen (CN)
- (73) Assignee: **JUHEYUAN SCIENCE & TECHNOLOGY CO., LTD.**, Shenzhen (CN)

(**) Term: **15 Years**

(21) Appl. No.: **29/776,211**

(22) Filed: **Mar. 29, 2021**

(30) **Foreign Application Priority Data**

- Dec. 3, 2020 (CN) 202030740407.4

(57) **CLAIM**

The ornamental design for a battery, as shown and described.

DESCRIPTION

FIG. 1 is a front, right, and top perspective view of a battery;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken (dashed) lines show portions of the battery that form no part of the claimed design.

1 Claim, 7 Drawing Sheets
